UNITED STATES PATENT OFFICE.

JUSTUS HATTEMER, OF WEST NEW YORK, NEW JERSEY, ASSIGNOR TO HARDMAN, PECK & COMPANY, OF NEW YORK, N. Y., A CORPORATION OF NEW YORK.

TRACKER-BAR.

No. 873,545.

Specification of Letters Patent.

Patented Dec. 10, 1907.

Application filed May 14, 1907. Serial No. 373,610.

To all whom it may concern:

Be it known that I, JUSTUS HATTEMER, a citizen of the United States, residing at West New York, in the county of Hudson and State of New Jersey, have invented 5 certain new and useful Improvements in Tracker-Bars; and I do hereby declare the following to be a full, clear, and exact description of the invention, such as will 10 enable others skilled in the art to which it appertains to make and use the same.

This invention relates to tracker-bars, and has for an object to provide a tracker bar for a self-playing instrument or for an instrument 15 player adapted to use music sheets arranged for varying compasses.

It is well known that the piano player ordinarily in use is adapted for use of music sheets with a compass of sixty-five actions, 20 such actions applying to both white and black keys upon the piano. It is also further well known that there is a large quantity of music which cannot be properly rendered within the compass of sixty-five 25 actions and to provide for such music, music sheets are now employed adapted to actuate eighty-eight actions, representing white and black keys.

It is an object of this invention to provide 30 a single tracker bar adapted by a simple shifting thereof to present either sixty-five or eighty-eight holes or openings to operate in association with the music sheets just mentioned.

35 A further object of the invention is to provide in a tracker bar a rotatably movable member having a row or series of sixty-five openings extending in a line in parallelism with the axis and another row or series of eighty-eight openings extending in parallelism 40 with both the axis of the other row and with tubes connecting such openings with the several actions.

A further object of the invention is to 45 provide a tracker bar of the kind described and with means for closing one series of openings while the other series is being employed and with a further means connecting both sets of openings with the actions.

50 With these and other objects in view, the invention comprises certain novel constructions, combinations and arrangements of parts, as will be hereinafter fully described and claimed.

55 In the drawings:—Figure 1 is a view in

vertical, transverse section of the tracker bar forming the subject-matter of this application, together with associated parts shown conventionally. Fig. 2 is a fragmentary view in front elevation of the tracker bar and associated parts. Fig. 3 is a detail view of modified form for connecting the tracker bar with the actions.

Like characters of reference designate corresponding parts throughout the several views.

The improved tracker bar is mounted between the usual and ordinary cheek plates 10 disposed either within a self-playing piano or within a piano player and between 15 which is journaled a take-up spool or roller 11 and removably journaled re-wind spool 12 carrying the music sheet 13. Between the spools 11 and 12 is mounted a tracker bar consisting of a segment of pipe 14, such 20 segment being in any approved proportion of the entire pipe and here shown as approximately two-thirds. The pipe is journaled in any approved manner as by means of a disk or end plate 15, and a stud 16 extending 25 therefrom into the cheek plates 10.

The pipe or tracker bar 12 is provided 30 with a row or series of openings 65 extending in parallelism with the axis of the tracker bar and with short tubes or nipples 17 in 35 communication each with one of the holes 65 and extending within the pipe. As the holes 65 are arranged very close together it is found desirable to stagger the extremities of the nipples 17 to permit the flexible tubes 40 18 to be easily and properly placed thereon. A second row of holes or openings 88 is provided 45 in parallelism with the axis of the tracker bar, and with the row of holes 65 and nipples 19 employed upon which are placed 50 the flexible tubes 20. The flexible tubes 18 and 20 engage at their opposite ends nipples 55 21 and 22 properly positioned in the action box 23. It will be understood that the pipes 60 corresponding with the pipes 18 communicate 65 with the same action, that is, the pipe 20 representing middle C upon the piano is in communication with the same action as the pipe 18 representing middle C. As the 70 longitudinal extent of the openings 88 is 105 practically equal to the longitudinal extent of the openings 65 it is obvious that the openings 88 are nearer together than the openings 65 and that the corresponding flexible tubes extending from said openings 110

115

while coincident at the middle of the tracker bar will vary a considerable distance toward the end of the tracker bar, the extreme tubes from the holes 88, of course, communicating 5 with actions to which no tubes lead from the holes 65.

Any approved means for rotating the tracker bar 14 is provided as the knob 24, and means for closing the row of openings 10 not in use is provided in a plate or board 25 pivoted as at 26 above the tracker bar and provided with a resilient or elastic member 27, preferably of leather positioned to bear upon the tracker bar and to cover simultaneously 15 all of the holes 88 when the holes 65 are in operative position. Below the tracker bar a similar plate or board 28 is pivoted at 29, and a similar elastic member 30 positioned to cover all of the holes 65 when the 20 tracker bar is in the position shown in Fig. 1 in dotted lines, with the holes 88 in operative position.

Means for clamping the elastic members 27 and 30 upon the tracker bar is provided 25 as the spring 31 extending between and having its opposite ends secured to the plates 25 and 28 whereby one of the rows of holes 65 or 88 are always covered by one of the elastic members 27 or 30.

30 Instead of employing two nipples as 21 and 22 for connecting the tubes 18 and 20 with the action a single Y-connection 32 as shown in Fig. 3, may be provided whereby the tubes 20 and 18 connect directly to the spaced ends 35 of the Y-connection, the single end being in communication with the action.

It will thus be seen that when the tracker bar is in the position shown in Fig. 1 in full lines the holes 65 are in position for operation 40 in connection with the music sheet 13, while the holes 88 are out of operation and covered by the elastic member 27. By grasping the knob 24 and rotating the

tracker bar in the direction indicated by the arrow to the dotted position the holes 88 are 45 exposed in operative position while the holes 65 are covered and eighty-eight hole music may be employed without other change.

What I claim is:—

1. A tracker bar composed of a segment 50 of a hollow cylinder, and provided with a plurality of series of openings extending in parallelism with the axis of the cylinder, nipples secured upon the inner surface of the segment and in communication with the 55 openings of the several series, flexible tubes extending from the nipples, the tubes of corresponding openings of the several series communicating with each other, covering members engaging the exterior surface of 60 the cylinder, and means to move the cylinder to bring one of the covering members into engagement with one of the series of openings.

2. A tracker bar composed of a segment 65 of a hollow cylinder provided with a plurality of series of openings extending in parallelism with the axis of the cylinder, a plurality of nipples rigidly secured to the interior surface of the cylinder in series corresponding to and communicating with the openings, flexible tubes secured to the nipples, and extending through the open side of the segment, means to rotate the segment upon its axis, and covering members bearing 70 yieldingly upon the exterior surface of the segment, and positioned each to cover one of the series of openings when the segment is moved.

In testimony whereof I affix my signature 80 in presence of two witnesses.

JUSTUS HATTEMER.
